Primary Examiner — Patricia Palasik

(74) Attorney, Agent, or Firm — Schroeder & Siegfried, P.A.

(57) **CLAIM**

The ornamental design for an oxygen acetylene torch handle, as shown and described.

DESCRIPTION

FIG. 1 is a perspective view of an oxygen acetylene torch handle showing my new design;

FIG. 2 is a front elevational view;

FIG. 3 is a rear elevational view;

FIG. 4 is a right side elevational view;

FIG. 5 is a left side elevational view;

FIG. 6 is a top plan view; and,

FIG. 7 is a bottom plan view.

The broken lines in the drawings represent environmental structure and form no part of the claimed design.

1 Claim, 4 Drawing Sheets
